ALBERT O. CRANE, OF BOSTON, MASSACHUSETTS.

Letters Patent No. 84,861, dated December 15, 1868.

IMPROVED HEEL FOR BOOTS AND SHOES.

The Schedule referred to in these Letters Patent and making part of the same.

Be it known that I, ALBERT O. CRANE, of Boston, in the county of Suffolk, and Commonwealth of Massachusetts, have invented a new and improved Rotating Heel for Boots and Shoes, and a new mode of fastening the same to the sole; and I do hereby declare that the following is a full, true, and exact description thereof, reference being had to the accompanying drawings, and to the letters of reference marked thereon.

My invention consists in providing a heel, or that part of the heel known among shoemakers as the "top-lifts," (being in thickness about equal to two or three of the last or top-risers of the heel, as usually made,) so constructed, and with such a device for fixing the same upon the sole of the shoe, as to be easily put on, and when on to be firm, and easily revolved.

I am aware that heels capable of being revolved after they are fastened upon the boot have been heretofore made, but they are, so far as I know, open to the objections following, that is to say, they are fastened from the inside, and are thus inconvenient. Also, when revolved, they turn on the thread of the fastening-screw, instead of turning on the fastening-stud, and thus it became loose. These, and other objections, my present improvements entirely overcome, as I believe.

My heel may be applied directly to the sole of the boot or shoe, and made of sufficient thickness for that purpose, but I prefer to apply them to a heel partly constructed upon the boot or shoe, and employ them in the place or stead of the two or three top-lifts or risers; and it is as so applied and constructed that I shall describe them.

I make the heel of any suitable material, (though I prefer some rubber compound,) round in form, and about one-half an inch in thickness.

If the revolving qualities are wholly or in part dispensed with, then an oval, or any form may be adopted.

Through the centre I make a circular hole, diminishing in diameter from the outer to the inner side or end, thus giving to it the form of a section of a cone.

I make a stud, likewise, in form, the section of a cone, (I prefer it to be of type-metal,) fitting snugly into this hole, and having the outer surface sufficiently smooth to permit the heel to revolve upon it without much friction. This stud should be about as long as the heel is thick. It is perforated, to receive the fastening-screw, and the larger end is bored out, so as to countersink the screw.

For lightness, and economy of stock, I prefer to countersink the screw about one-half the length of the stud.

The inside of the smaller end of the stud is made with a tapering shoulder, fitting the form of the under side of an ordinary screw-head, and the hole therein is of the size of the fastening-screw, thus giving to the screw a firm hold, and to the stud sufficient strength to hold the heel firmly in its place on the shoe when the screw is driven into the sole.

The walls of the inner or smaller end of this stud, it will be seen, are much thicker than those of the larger end, by reason of the latter having been bored out to countersink the screw, and they are thus able to bear the greater strain that comes upon them in holding, by means of the screw-head, the stud and heel to the sole.

Upon the inner edge of this stud I make one or more

points or projections, that enter into the sole of the shoe when the stud is screwed down, and thus effectually prevent the turning of the stud or screw when the heel is revolved.

When this stud is inserted in the hole in the heel, and the whole screwed upon the boot, the heel will, with little force, be made to revolve upon the stud, and the whole is ready for use.

In putting on the heel, it is better to make holes in the sole, to receive the screw and the points on the stud.

It will be seen that, as the heel is held upon the shoe only by this stud, it is important that it should have a diameter, thickness, and taper corresponding to the size of the heel. For this purpose I have various sizes of studs, according to the size of the heels. But for the ordinary size of men's boots, say as large as No. 7, I make the stud about eleven-sixteenths of an inch in diameter at the larger, and one-half an inch at the smaller end, and one-twelfth of an inch in thickness in the walls at the larger end when the screw-head is countersunk. But these proportions and dimensions must vary, not only with the size of the heel, but with the materials used.

I do not confine myself to fastening these heels on the sole with a screw only; sometimes I prefer a nail driven through the stud, and clinched on the inside of the shoe, having a head shaped to fit the inclined shoulder of the stud.

The annexed drawings show the features of my said invention with substantial minuteness and accuracy.

Figure 1 represents the heel fastened upon the boot, and ready for wear.

Figure 2 represents the stud.

Figure 3 represents a vertical section of the heel and sole as fastened together in fig. 1, drawn through the middle of the heel.

Figure 4 represents a part of a boot prepared to receive my heel, made as particularly hereinbefore described, with the stud upon it.

In these drawings, the letters represent the features of my improvement, as follows, viz:

a, the heel.

b, the stud.

c, the heel-part of the boot upon which my improved heel is intended to be placed.

d, the space cut away in the stud, for countersinking the screw.

e, the points on the stud.

f, the screw.

I claim—

1. Heels, made substantially as I have described, and so constructed that they may be revolved upon the stud by which they are fastened upon the boot or shoe.

2. A stud, so formed that it will hold the heel upon the boot or shoe, and remain in its place while the heel is revolved.

3. The combination of the heel and stud, made substantially as and for the purposes described.

ALBERT O. CRANE.
